UNITED STATES PATENT OFFICE.

WADIE J. FOX, OF DOUGLAS, OKLAHOMA.

SWITCH-OPERATING MECHANISM.

1,295,149.

Specification of Letters Patent.

Patented Feb. 25, 1919.

Application filed June 22, 1918. Serial No. 241,389.

To all whom it may concern:

Be it known that I, WADIE J. Fox, a citizen of the United States, residing at Douglas, in the county of Garfield and State of 5 Oklahoma, have invented new and useful Improvements in Switch-Operating Mechanism, of which the following is a specification.

This invention relates to railway switch 10 operating mechanisms and aims to provide means by which the engineer of a train approaching a switch may operate the latter without stopping the train.

A further object of the invention is to 15 provide means by which the switch may be operated for either the main track or side track, the position of the switch being determined by a device mounted upon the engine and manually operated to throw the switch 20 to the desired position.

To this end the invention includes a track device positioned in advance of the switch and embodying suitable mechanism for controlling the position of the switch points, the 25 said mechanism controlling a signal mounted upon a casing of the track device and further including slidably mounted trip elements positioned for contact with a car device, so that the approaching train may 30 control the position of the switch.

The invention further includes the following novel details of construction, combination and arrangement of parts to be herein- 35 after more specifically described and illustrated in the accompanying drawings, in which:—

Figure 1 is a plan view of a switch, showing a main track and a siding and the position of the track devices and their connection with the switch points;

Fig. 2 is an enlarged side elevation of the track device;

Fig. 3 is a similar view with the face plate of the casing broken away to more clearly 45 show the inner mechanism;

Fig. 4 is a sectional view on the line 4—4 of Fig. 2;

Fig. 5 is a similar view on the line 5—5 of Fig. 2; and

Fig. 6 is a detail perspective view of one of the slides.

Fig. 7 is a detail perspective view of the train device.

Referring to the drawings in detail, wherein like characters of reference denote corresponding parts, the rails of the main

track are shown at A and the rails of the siding at B. The switch points C are connected by a transversely slideable bar D and this bar has connected to one end one arm 60 10 of a three armed lever E, the latter being pivotally mounted as shown at 11. Another arm 12 of the lever E has pivotally connected thereto one end of a rod 13, the opposite end of this rod being connected to the mechanism of the track device F. The other arm of the three armed lever E is shown at 14 and has connected thereto one end of a rod 15, the opposite end of this rod being connected to the track device G. The trans- 65 70 75

verse bar D has its opposite end connected to one end of a bent lever 16, which is pivoted at 17. The opposite end of this lever has connected thereto one end of a rod 18, whose opposite end is connected to the track device H. These track devices are operated by a train device set for contact with the track devices so as to operate the switch. As these track devices F, G, and H are similar in construction, only one of these 80 85 90 95 100 105 110 devices will be illustrated in detail and described. Each of the track devices is contained within a suitable casing 19, preferably of rectangular shape and having a face plate 20 which carries the operating mechanism, the said face plate being removably secured to the casing so that access may be obtained to the said mechanism. Mounted upon the rear of the face plate 20 are upper and lower guides 21 and 22 and an intermediate guide 23, these guides being riveted to a plate 24 spaced from the inner side of the face plate 20 to provide grooves or channels 25. Mounted for sliding movement within these grooves or channels are plates 26 and 27, the slide 26 being herein- after referred to as the upper slide, while the slide 27 will be referred to as the lower slide. Each of the slides 26 and 27 is provided with spaced lugs 28 and pivotally mounted between these lugs upon pins 29 are trip elements 30. The lugs 28 extend through parallel slots provided in the face plate 20, the said slots being horizontally disposed so that the slides 26 and 27 may be capable of horizontal movement. Each of the trip elements 30 is provided upon opposite sides with laterally extending wings 32, these wings carrying at their outer ends rollers 33 for contact with the face plate 20, so that the trip elements will be prevented from pivotal movement by such contact. Located

between the slots near the ends thereof are openings 34 through which the wings 32 are adapted to pass, so that when the slides 26 and 27 reach the limit of their movement, 5 the wings 32 will enter the openings and permit the trip elements to move upon the pins 29 out of their normally right angular position.

Positioned behind each of the openings 34 10 is a flat spring 35, one end of the latter being secured upon a pin 36. These pins are positioned within channel bars 37 carried by a plate 38, the latter being spaced from the face plate 20 and providing an additional 15 casing or housing for the mechanism. The free ends of the springs 35 are positioned so as to cover the openings 34 and when the wings 32 contact with the springs, the latter will yield so as to permit the said wings 20 to enter the openings and allow the pivotal movement of the trip elements. To further insure the proper positioning of the springs 35, the coiled springs 39 are secured to the plate 38 and bear against the flat springs 35.

25 The slides 26 and 27 are cut away as shown at 40 to permit of the proper yielding movement of the springs 35, the cut away portion being so proportioned however that when the trip elements are at one end of their 30 movement, the opening 34 at the opposite end of the slots 31 will be covered by the slide. This prevents entrance of dust or dirt through the openings and renders the device dust-proof.

35 Mounted upon shaft 41 between the slides 26 and 27 is a pinion 42, which is adapted to engage rack teeth 43 and 44 provided in the adjacent edges of each of the slides 26 and 27 respectively. The shaft 41 is journaled in 40 suitable bearings provided in the face plate 20 and the plate 38, the said shaft extending inwardly beyond the latter plate and having mounted thereon an arm 45. The outer end of this arm has connected thereto one end 45 of a rod 46 and the opposite end of this rod is connected to one arm of the bell crank 47 pivotally mounted as shown at 48 within the casing 19. The other arm of the bell crank has connected thereto through the medium 50 of a link or bell crank one end of one of the rods 13, 15 or 18 as the case may be. Also mounted upon the shaft 41 is a spring arm 49, the free end of which enters a radial slot 50 formed in a disk or wheel 51, the latter being mounted upon one end of a vertically disposed shaft 52 having bearings in the top 55 of the casing 19. This shaft extends through the casing and carries signal arm 53 and a signal lamp 54 of the usual construction.

60 The casing which contains the foregoing described mechanism is adapted to be mounted adjacent the track with the trip elements 30 extending inwardly or toward the track for contact with a suitable train device. 65 This train device is preferably positioned

upon the engine and includes a plate 55, the main body portion of which is offset to provide flanges 56. Mounted for rotation in bearings formed in the plate 55 are rods 57, these rods extending within convenient 70 reach of the engineer and being provided with handles 58 to facilitate their operation. Mounted upon each of the rods 57 is an arm 59, this arm being adapted to extend through slot 60 in the plate 55. The arms 59 of the rods 57 are spaced apart a vertical distance equal to the distance between the trip elements of the slides 26 and 27. The train device is so positioned that when the arms 59 are moved outwardly through the slots 60, 80 they will contact with the trip elements of the slides 26 and 27. As each of the arms 59 is positioned upon a separate rod, either arm may be manipulated for contact with its respective trip element, the rod 57 being 85 rotated to project the arm 59 through the slot 60, the adjacent end of the slot forming a stop to limit the movement of the rod in one direction.

In the operation of the invention when it 90 is desired to enter the siding with the switch in the position shown in Fig. 1, the engineer of an approaching train will rotate the rod 57 of the upper arm 59 to project this arm through its slot 60. This will cause said arm 95 to engage the upper trip element 30 of the slide 36 of the track device F, moving the said slide in a manner to rotate the shaft 41 and operate the switch and signal. When the slide thus operated reaches the limit of 100 its movement, one of its wings 32 will enter the opening 34 permitting the trip element to swing upon the pin 29, so that the arm 59 will pass the trip. As soon as the arm 59 has passed, the trip element will be restored 105 to its normal position under the influence of the springs 35 and 39 so as to be in position for operation by the train approaching from the opposite direction. During the movement of the slide engaged by the arm 59, the 110 other slide will be moved in reverse direction through the action of the pinion 42.

It is believed that when the foregoing description is read in connection with the accompanying drawings, that the operation 115 and advantages of the invention will be apparent and that a more extended description is unnecessary. The invention is susceptible of various changes in its form, proportions and minor details of construction and the 120 right is reserved to make such changes.

Having described the invention, what is claimed is:—

1. A switch operating device embodying 125 a track mechanism, said mechanism including a rotatably mounted shaft, a slide mounted for horizontal movement, means connecting the slide with the shaft whereby the operation of the former will rotate the latter, a trip carried by said slide, a train 130

device adapted to contact with said trip to move the slide, means whereby said trip will be automatically released from contact with the train device at the end of the movement 5 of the slide and means connecting the rotatably mounted shaft with the switch points to operate the latter upon rotation of the shaft.

2. A switch operating device embodying a track mechanism, said mechanism including 10 a casing positioned adjacent the track, a rotatably mounted shaft therein, a slide mounted for horizontal movement within said casing, a trip element pivotally secured 15 to said slide and mounted for movement upon the outside of the casing, means for holding the trip element against pivotal movement during the horizontal movement of the slide, means for permitting the pivotal 20 movement of the trip element when the slide reaches the limit of its movement, a train device, means whereby said train device may be set to contact with the trip element to operate the slide and means connecting the 25 rotatably mounted shaft with the switch points to operate the latter upon rotation of the shaft.

3. A switch operating device embodying a track mechanism, said mechanism including 30 a casing positioned adjacent the track, a rotatably mounted shaft therein, a slide mounted for horizontal movement within said casing, a trip element pivotally secured 35 to said slide and mounted for movement upon the outside of the casing, means including laterally extending wings engageable with the face of the casing for holding the trip element against pivotal movement during the horizontal movement of the 40 slide, means for permitting the pivotal movement of the trip element when the slide reaches the limit of its movement, a train device, means whereby said train device may be set to contact with the trip element to 45 operate the slide and means connecting the rotatably mounted shaft with the switch points to operate the latter upon rotation of the shaft.

4. A switch operating device embodying 50 a track mechanism, said mechanism including a casing positioned adjacent the track, a rotatably mounted shaft therein, a slide mounted for horizontal movement within said casing, a trip element pivotally secured 55 to said slide and mounted for movement upon the outside of the casing, means for holding the trip element against pivotal movement during the horizontal movement of the trip element when the slide reaches 60 the limit of its movement, a train device,

means whereby said train device may be set to contact with the trip element to operate the slide and means connecting the rotatably mounted shaft with the switch points to operate the latter upon rotation of the shaft. 65

5. A switch operating device embodying a track mechanism including a casing positioned adjacent the track, the rotatably mounted shaft therein, a slide mounted for horizontal movement within said casing, 70 spaced ears carried by said slide and operating through slots in one wall of the casing, a trip element pivoted between said ears, laterally extending side wings engageable with the face plate of the casing for holding 75 the trip element against pivotal movement during the horizontal movement of the slide, yieldable means positioned within the casing behind openings in the face plate for permitting pivotal movement of the trip 80 element when the slide reaches the limit of its movement, means whereby the slide will cover the openings in the face plate to render the casing dust proof, a train device, means whereby said train device may be set 85 to contact with the trip element to operate the slide and means connecting the rotatably mounted shaft with the switch points to operate the latter upon rotation of the shaft. 90

6. A switch operating device embodying a track mechanism, said mechanism including a rotatably mounted shaft, slides mounted for horizontal movement upon opposite sides of said shaft, means connecting the said slide and shaft whereby the operation of one of the slides will rotate the shaft and move the other slide in a reverse direction from the first mentioned slide, means connecting the rotatably mounted shaft with the switch points for operating the latter, a signal controlled by said shaft and a train device for operating the slides. 95

7. A switch operating device embodying a track mechanism, said mechanism including a rotatably mounted shaft, slides mounted for horizontal movement upon the opposite sides of said horizontal shaft, a rack and pinion connection between said slides and shaft whereby the operation of one of the slides will rotate the shaft and move the other slide in a reverse direction from the first mentioned slide, means connecting the rotatably mounted shaft with the switch points for operating the latter, a signal controlled by said shaft and a train device for operating the slides. 100 105 110 115

In testimony whereof I affix my signature.

WADIE J. FOX.
